CLAIM

The ornamental design for a wall-mounted DC charging pile, as shown and described.

DESCRIPTION

1. Wall-mounted DC charging pile

1.1 : Front

1.2 : Back

1.3 : Left

1.4 : Right

1.5:Top

1.6 : Bottom

1.7 : Perspective

The broken lines depict portions of the wall-mounted AC charging pile that form no part of the claimed design.

The use of the present design product: offering charging services to electric cars; The design gist of the present design product: the shape of the product; The picture or photo best showing the design gist of the present design product: perspective view.

1 Claim, 7 Drawing Sheets
